UNITED STATES PATENT OFFICE.

EARL C. STAFFORD, OF PHILADELPHIA, PENNSYLVANIA, ASSIGNOR TO THE UNITED STATES TRAIN SIGNAL COMPANY, OF PORTLAND, MAINE, A CORPORATION OF MAINE.

AUTOMATIC TRAIN-CONTROL SYSTEM.

Application filed October 2, 1922. Serial No. 591,939.

My said invention relates to an improved automatic block train control system embodying various improvements over the system disclosed in my prior Patent No. 1,327,176 January 6, 1920, and it is an object of the same to provide interlocking mechanical and electrical controlling devices by means of which a high degree of safety may be secured since they absolutely prevent a following train from entering a block already occupied.

A further object of the invention is to provide an electrically operated block train control in which the circuit is normally closed and in which breaking of the circuit whether due to the presence of another train on the block or a defect in the signal system or any other cause will serve to stop the train.

Another object of the invention is to provide such a system with interlocking safety devices that shall provide effectively against failure to operate.

Another object is to provide means whereby the engineer may increase the pressure on the brakes for an automatic stop without leaving his cab although he is precluded from releasing the brakes from this position after an automatic stop.

Other objects and advantages of the device will appear from the following specification.

Referring to the accompanying drawings, which are made a part hereof and on which similar reference characters indicate similar parts,

Figure 1 is a side view of a locomotive equipped with my devices,

Figure 2 a similar view of a tender to be attached to said locomotive,

Figure 3 an elevation of a ramp actuated shoe and parts cooperating therewith,

Figure 4 a right-hand elevation of parts shown in Figure 3,

Figure 5 a section on line 5—5 of Figure 3.

Figure 6 a detail of a portion of the ramp rail and supporting means therefor,

Figure 7 a view partly in section showing parts of the air brake system and a magnetic control valve therefor,

Figure 8 an elevation of a manually reset stick relay forming a part of the system, with the casing in section,

Figure 9 a plan of the same with the casing in section,

Figure 10 a section on line 10—10 of Figure 11,

Figure 11 a side view of the pump shown Figure 10,

Figure 12 a detail of the parts shown in Figure 10,

Figure 13 a diagrammatic view of the parts carried by the engine and tender with their connecting circuits, all shown in their normal position while the train is running,

Figure 14 a diagram indicating the relation of parts after the contact shoe or slider has engaged a live ramp,

Figure 15 a diagrammatic view indicating the result of engagement with a dead ramp,

Figure 16 a similar view indicating the position of parts when the hand reset for the system has been closed and the train is proceeding at low speed,

Figure 17 a diagrammatic view of a portion of a track in a double track railroad.

In the drawings reference character A indicates a conventional locomotive, B a conventional tender therefor, C a mechanism 80 casing, D a manual resetting device, E a battery box, F an automatic brake valve, G an electrically-controlled valve, and H a speed governor, the parts so located on the engine and tender being the principal elements in my system which elements will hereinafter be described in detail. Figure 1 also shows a sealed three-way cutout cock K, a double-heading cutout cock L and a ramp M, the latter being mounted alongside the track and preferably on the ties.

Referring to Figure 6 a portion of the ramp M is here shown as being supported on two ties 30—30 by brackets 31 bolted to the ties, each bracket supporting a threaded member 32 which at its upper end is fixed to the ramp rail, the threads at opposite ends permitting adjustment of member 32 to correspond to the varying distances between the ramp and the ties at intervals along the track, each ramp having a downwardly inclined portion at each end about 10 feet long and a ten foot horizontal section at the middle.

The ramps are adapted for contact by shoes 33 which engage at the under side of the ramps, and the same operation takes place whether the train is running forward or back.

Figures 3, 4 and 5 show enlarged views of a shoe 33 and the parts adjacent thereto.

Shoes 33 are supported by a pivot 34 on brackets 35 fixed to a base plate 36 of mechanism casing C by bolts 37, the bolts being insulated from the bracket by insulation 38 and the bracket being separated from the base plate by insulation 39. The pivot shaft 34 has a collar 40 fixed to it by pins 41 and is fixed to the bracket by pins 41'. Torsion springs 42 are each secured at one end to the collar and at the other end to the shoe. Brass bushings 34' separate the brackets 35 from pivot 34. Projecting rearwardly from the shoe is an arm 43 that bears on the underside of a contact block 44 on a slidable tappet 44' mounted in guides 45 on the base plate. The brackets 35 and connected parts are covered by a housing 45' to protect them from injury.

The tappet extends up into a housing 46 having a cover 47 at its front side with a suitable latch for keeping it closed. Within the housing is an electromagnet 48 connected by a wire 49 to the shoe 33 and by another wire 50 to a ground 51 (Figure 13). An armature 52 is supported by a weighted bracket pivoted at 53, this bracket having at its upper end a detent 54 cooperating with a hook 55 fixed to the tappet. The bracket also carries a laterally extending hook 56 adapted to be engaged by a pin 57 on the slidable tappet. In case a shoe should be lost the corresponding tappet would fall and the pin 57 would engage hook 56, the weight of the tappet serving to pull the armature away from the magnet and so break the circuit through the valve G and stop the train as hereinafter set forth. Pin 57 also prevents closing of the circuit at 58, 59 unless the tappet is properly raised, due to its engagement with the hook 56. At the opposite side of the detent 54 is an insulated contact member 58 adapted to be engaged by a pair of contacts 59 mounted on and insulated from a support 60 fixed to the base. The tappet also carries a movable circuit controlling element comprising a support 61 and a series of blocks 61'. A spring 62 bears at one end against a guide 45 and at the other against a shoulder on the tappet and tends to force the tappet downward. These blocks are arranged to cooperate with spring contacts 63 on a circuit closing block 64 fixed to the base 36.

55 Air brake control valve.

The air brake control appliances (Figures 1 and 7) include a train pipe 64', an engineer's brake valve 65, an automatic brake valve F, a sealed three way cock K and a double-heading cut-out cock L, the old and well-known parts being shown diagrammatically and on a reduced scale. A pipe 66 leads from the operator's brake valve to the automatic brake valve which is connected by pipes 67 and 68 and a connecting passage

through the three way cock to the train pipe for operation in the ordinary manner. An emergency by-pass pipe 69 leads from the operator's valve directly to the three way cock and it will be seen that by reason of the presence of this by-pass the operator's valve may operate independently of the automatic brake valve by turning the handle 70 from the full line position where it is held by a seal 71 to the dotted line position. Such operation is, however, recorded due to the breaking of the seal. In ordinary practice the operator's valve can also be operated for emergency application of the automatic brake valve, as will appear hereinafter. The electrically controlled valve G controls brakes without interfering with the autoprise an electro-magnet 72 with an armature 73 formed at its upper end as a valve to close a down going branch of an air passage 74, this branch leading to exhaust openings 75. So long as the electro-magnet is energized the passage will be closed by said valve. When the magnet is deenergized the inlet end of the passage will be closed by a valve 76 fixed to or supported by the armature. The air in these passages comes through the pipe 77 connected to the main reservoir and in the position of parts shown in the drawings goes through the passage-way 74 to a pipe 78 leading to a chamber 78' in the automatic brake valve underneath the piston 79 and holds the piston against a leather washer 80. The piston 79 has a two-part stem 81 on which are a pair of valves 82 and 83 the valve 83 being adapted to close the passage through the brake valve from the train pipe to the exhaust which in this instance consists of an aperture in a plug 81, the aperture being reduced at its outer end to form a small leak port. When the air pressure under the piston fails the piston moves downward, the upper valve 82 seats itself and so closes the passage through the automatic brake valve to prevent passage of air from the main reservoir. It does not interfere with the operation of the brakes by means of the operator's valve as valve 82 is merely a check valve movably connected to valve 83 by joint 82'. The electro-magnet 72 is energized by a circuit comprising a conductor leading to ground 86 and another conductor 87 leading to the uppermost spring contact 63 on the block 64. A conductor 88 is also adapted to contact under certain circumstances with said segment, this conductor being connected to a battery and then to ground. I may also mount on the valve body a set retaining valve body 89 having a passage 105 opening into the automatic brake valve, this passage being normally closed by a valve 90 under adjustable spring pressure. When the air pressure is admitted to the automatic brake valve by the lowering of piston 79 the 110

valve 90 will be forced back and the pressure will be quickly reduced by escape of air through passages 91 after which leakage will continue slowly by way of leak port 84. An alert engineman, by closing the hand reset promptly after the train stops can check the flow of air from the exhaust ports and thus save air, such action closing the circuits shown in Figure 16 and energizing electro-magnet 72 thereby admitting air to passage 78 to lift piston 79 and close valve 83.

Hand reset stick relay.

The tender shown in Figure 2 carries a manually reset circuit breaker for a wiring system on the train, details of which are shown in Figures 8 and 9 and the location of which with reference to the remaining mechanism is illustrated in Figures 13 to 16. Referring to Figures 8 and 9 the device comprises an outer casing enclosing the entire device and supporting an inner casing 103 containing the core of an electromagnet connected to the battery in box E by conductors 104 and 105 (Figs. 8, 13 and 16). The electromagnet has an armature consisting of a disk 107 to which a brass rod 106 is connected by a screw-thread to permit adjustment of the rod relatively to the disk. At its upper end the rod carries a fiber pin to engage a circuit closer. When the electromagnet is de-energized the disk and rod fall so far that the head 108 of the rod rests on a fiber pin 109 in the upper end of a rod 109 located in a bore at the lower end of the casing, said rod having a collar to support it on the floor of the casing. The headed rod serves to lift the armature into the field of operation of the electromagnet, the lowermost position of the disk being such that it can not be elevated merely by energization of the electromagnet. The magnet casing has a lower extension 110 secured by screws to the outer casing and is held in place at its upper end by a U-shaped bracket 111, the bracket having its arms bent laterally at their upper end and having also a bore through which the brass rod passes. Insulating washers 112 are applied to said arms and a post 113 extends through each of them thus providing a connector on the one arm for a contact 114 adapted to engage a pair of contacts 115 mounted on the other arm. A conductor 116 leads to the contact 114 and the contacts 115 are connected respectively to conductors 117 and 118 by the posts 113. The armature being lifted and the magnet energized the rod 106 will be maintained in the position shown, and so will hold the contact 114 against the two contacts 115.

Safety speed controlling device.

The safety speed controlling device is

shown in detail in Figures 10 to 12 and also appears in Figures 1, 13 to 16. This device may be operated by a special motor but is here shown as actuated from the cross head 119 by a connection comprising a link 120 and a rock arm 121 secured to a rockshaft 122. The rockshaft 122 has a pair of cranks connected respectively by links 123 and 124 to pump pistons 125 and 126. These pistons operate in parallel bores in a cylinder 127 communicating with a cylinder 128. The cylinder 128 contains a piston 129 having near its upper end a transverse slot to receive the enlarged head of a rockarm 130 on a shaft 131. This shaft also carries a cam 132 adapted to actuate a lever 133 by engagement with a similar cam 133' thereon. The lever 133 is connected to a flexible contact member 134 adapted to engage a second contact 135 to close a circuit diagrammatically shown in the remaining figures. Should the pump fail to work the piston 129 will remain in its lowest position and the cam 131 will fail to ride under and lift up the cam on lever 133. A float 136 rests on the oil in the lower chamber of the casing H and this float carries a rod engaging a recess in the under side of the rockarm 130. The float holds the arm 130 up in substantially the position shown, but if the oil falls too low the arm falls and breaks the circuit. A leak passage 137 on the piston permits the oil to bypass from under the piston when the level in the casing is low. In the absence of such a passage it will be seen that the piston might be held up until the casing was practically dry. The oil from the leak passage 137 passes through leak ports 137' in the cylinder 128 at a distance from the bottom of the cylinder corresponding to the distance between the bottom of the piston and the upper end of leak passage 137. By this arrangement the piston can gradually sink to the bottom of the cylinder. The ports 137' are so located as to serve also to prevent excessive pressure by permitting the oil to escape after the piston has been raised to a sufficient height. A pipe 138 is connected to the cylinder adjacent its lower end and extends upward into a casing provided with a pin valve 139. A pipe 140 leads back into the chamber from the other side of the pin valve. This valve provides means for adjusting the escape passage to vary the effect of the pump on the piston 129 and thus vary the predetermined maximum speed when the signal-controlled automatic stop devices are out of action.

Operation.

In the operation of my device the position of parts on the train during normal operation between ramps will be as shown in Figure 13 and at this time current will

pass from the engine battery through conductor 88, block 61', conductor 87, magnet G, and conductor 85 to ground at 86. While the train is moving between ramps the parts will remain in the position of Figure 1, operation of the brakes being prevented by the valve on armature 73 which is held in place as in Figure 7 to prevent escape of air from the braking system.

10 When the shoe 33 contacts with a live ramp it is moved as in Figure 14, raising the tappet 44' above the detent 54. The magnet 48 becomes energized as explained below, and attracts the armature 52 carrying detent 54 and contact 58. This position of the armature will permit the tappet to return to normal position after the ramp is passed and also closes the circuit through contacts 58 and 59, 59. When the tappet is in raised position the current from the engine battery 141 passes through conductor 88, block 142, conductors 143 and 118, contacts 59, 58, 59, conductor 144, magnet G, and conductor 85 to ground. The group of contacts 63 should preferably be so spaced that one of the two circuits for energizing magnet G will be closed just before the other is opened thus preventing loss of pressure in the brake system.

20 It may be stated here that in the case of a "live" ramp current passes through a road-side battery 145, a pivoted circuit closer 146, a stationary contact 147, a conductor 148, the ramp M, shoe 33, conductor 49, magnet 48 and so to ground at 51. The track is divided into a plurality of blocks as indicated at N, O, P in Figure 17 and each block has connected across the rails a track battery 149, the battery energizing a circuit comprising a conductor 150 leading to one rail of the track, a conductor 151 leading from this rail to an electromagnet 152, a conductor 153 leading from the magnet to the other rail of the track and a conductor 154 extending from that rail to the battery. The electromagnet 152 is normally energized by this circuit to hold the circuit-closer 146 in closed position. Assuming the system here shown to be used with "home" and "distant" signals of the type shown in my Patent 1,327,176 and the train to be moving in the direction of the arrow it will be seen that the home signal at the right hand side of Figure 17 is evidently set at danger, the train being in the block O and short circuiting the battery of that block whereby the corresponding magnet 152 is deenergized and the switch is open thereby producing a "dead" ramp. At the same time the "distant" signal in the block N will have been moved to caution position.

Figure 15 shows the position of parts resulting when a train encounters a dead ramp such as is shown at the left of Figure 17. The shoe 33 will of course raise the tappet

44' and inasmuch as magnet 48 is deenergized by reason of the opening of the circuit at 146, 147, the detent 54 will be free and by reason of the weight at one side of its pivot it will be swung over against the tappet thereby engaging under the shoulder 55 and preventing the tappet from returning to its lowermost position. The circuit leading from the engine battery through conductors 88 and 87 will be broken as in Figure 14 and the circuit leading from the engine battery through conductors 88, 143, 118 and 144 will remain open due to the movement of the detent whereby the contact 58 is removed from contacts 59, 59. The electromagnet G being thus deenergized the armature 73 will fall, thus opening the valve. The air will escape and the brakes will be set.

After being thus stopped the engineer can nevertheless proceed at a low speed which may be predetermined according to the circumstances of the particular railroad or subdivision thereof. For this purpose the manual re-setting device or stick relay D is provided. It is located under the tender so that the engineman must get out of his cab to operate it. It will be seen that when this stick relay is moved to closed position as in Figure 16 by operation of the plunger rod 109 (Figure 8) a circuit will be closed from the engine battery 141 through conductor 88, block 142, conductor 143, contacts 115, 114, conductor 116, block 155, conductor 156, circuit closer 134 (Figures 10 and 16), stationary contact 135, conductor 104, magnet 103, conductor 105, and so to ground at 157. The magnet 103 serves to hold the hand reset stick relay in closed position against the action of gravity, but does not raise it when it has once fallen. A branch circuit is also closed by actuation of rod 109 through the engine battery 141, the conductors 88, 142, 143, the contacts 115, 116, 115, conductor 117, brake magnet G, and conductor 85 to ground at 86. At this time the tappet is locked in upper position but on encounter with a dead ramp will stop the train by breaking the connection between block 155 and wire 156, thus deenergizing magnet 103. To insure running only at a speed lower than a predetermined speed, the governor illustrated in Figures 10 to 12 is introduced into the system. So long as the desired low speed is maintained, the pumps 125 and 126 will raise the piston 129 only so high as to maintain the cam 132 under the cam on the lever 133 and thus hold the switch elements in closed relation to each other. Should a higher speed be attained at any time the pumps will be operated so rapidly as to raise the piston to a greater height and thereupon the cam on the rock arm will move the cam on lever 133, thus permitting the lever to fall and open the circuit. When this takes place

the magnet 103 becomes deenergized and the armature of the stick relay falls, interrupting the brake circuit and causing the air brakes to be applied. Should the pumps 5 fail to lift the piston 129 the cam 132 will pass the cam 133 in the other direction and allow the lever to fall thus opening the switch and causing the circuit via conductor 116 to be opened because of the failure of 10 magnet 103.

Should the train pass a live ramp while in the condition of Figure 16 the ramp will raise the tappet and, being electrified, it will also cause the magnet 48 to be energized. The magnet will attract its armature, thus retracting the detent 54 to permit the tappet to fall, and will also close the circuit at 58, 59, 59 until the ramp is passed. The parts are now in position to resume high 20 speed travel which may be continued until interrupted by a signal or some defect such as a broken rail, a break in the circuit or the like, which can produce an effect like that of a "stop" signal. The circuit through 25 wires 116, 156, block 155, etc., will be closed only when the train is proceeding at low speed under the conditions of Figure 16, and will be broken whenever a ramp is encountered by the shoe. This circuit when so 30 broken will not be restored, as the train is now traveling at increasing speed, and the control by the automatic stopping devices is now resumed.

By moving the lever 70 (Fig. 7) I may 35 cut out the entire automatic control and leave the train under control of the engineer alone. When this is done the seal 71 is broken to indicate the occurrence to a train inspector or other official.

40 The system is designed so as to be readily applicable to existing apparatus. It forms a reliable interlocking connection between the air brakes and the signal apparatus whereby trains may be fully controlled in 45 a predetermined manner.

Many variations in the system and parts 50 thereof may be made without departing from the spirit of my invention the true scope of which is indicated in the appended 55 claims.

While I have shown the pump in Figures 10 and 11 as driven by an oscillating shaft it may be connected to a rotating member of the locomotive by a silent chain or the like.

Having thus fully described my said invention, what I claim as new and desire to secure by Letters Patent, is:

60 1. A block control system for railway trains comprising train stopping means, a normally closed electric circuit restraining operation thereof, an auxiliary circuit adapted to restrain operation of the train stopping means, a circuit closer common to both circuits, a ramp for each block, a block-sig-

nal-controlled circuit for each ramp, a shoe on the train adapted to be actuated by a ramp for operating the circuit closer to open the main circuit at one point and close the other circuit at one point, a detent to hold the circuit closer in the actuated position, and an electromagnet in circuit with said ramp to inhibit the action of the detent when a clear track is indicated, substantially as set forth.

2. A block control system for railway 70 trains comprising train stopping means, a normally closed electric circuit restraining operation thereof, an auxiliary circuit adapted to restrain operation of the train stopping means, a circuit closer common to both circuits, a ramp for each block, a block-signal-controlled circuit for each ramp, a shoe on the train adapted to be actuated by a ramp for operating the circuit closer to open the main circuit at one point and close the other circuit at one point, a detent to hold the circuit closer in the latter position, and an electromagnet in circuit with said ramp to inhibit the action of the detent when a clear track is indicated, a part of the auxiliary 75 circuit being mounted on said detent whereby said circuit also is interrupted when the ramp circuit is broken, substantially as set forth.

3. A block control system for railway 80 trains comprising train stopping means, means normally restraining operation thereof including a normally closed main electric circuit, an auxiliary circuit also adapted to restrain operation of the train stopping means, a ramp for each block, a block-signal-controlled circuit for each ramp, means for alternately interrupting and restoring the two circuits in passing a live ramp, means for interrupting both circuits in passing a 85 dead ramp, a third controlling circuit for the restraining means, and a circuit closer common to the three circuits, substantially as set forth.

4. A block control system for railway 90 trains comprising train stopping means, means normally restraining operation thereof including a main electric circuit, an auxiliary circuit adapted to restrain operation of the train stopping means, a ramp for each 95 block, a block-signal-controlled circuit for each ramp, means for alternately interrupting and restoring the two train circuits in passing a live ramp, means for interrupting both circuits in passing a dead ramp, a stick 100 relay inaccessible while the train is moving for closing a third controlling circuit for the restraining means, and means to limit the speed of travel while said third circuit is closed, substantially as set forth.

5. A block control system for railway 105 trains comprising train stopping means, means normally restraining operation thereof including a main electric circuit, an auxiliary circuit adapted to restrain operation of 110

the train stopping means, a ramp for each block, a block-signal-controlled circuit for each ramp, means for alternately interrupting and restoring the two train circuits in passing a live ramp, means for interrupting both circuits in passing a dead ramp, a third controlling circuit for said restraining means, and a stick relay underneath a train unit for closing the same, substantially as set forth.

6. A block control system for railway trains comprising train stopping means, means normally restraining operation thereof of including a main electric circuit, an auxiliary circuit adapted to restrain operation of the train stopping means, a ramp for each block, a block-signal-controlled circuit for each ramp, means for alternately interrupting and restoring the two restraining circuits in passing a live ramp, means for interrupting both circuits in passing a dead ramp, a third controlling circuit for the train stopping means, a circuit closer for said circuit, a gravity-actuated armature adapted when its magnet is energized to hold said circuit closer in closed position, an electromagnet for the armature proportioned only to maintain the armature in circuit closing position, and manual means for raising the armature, substantially as set forth.

7. A block control system for railway trains comprising train stopping means, means normally restraining operation thereof, including a main electric circuit, an auxiliary circuit adapted to restrain operation of the train stopping means, a ramp for each block, a block-signal-controlled circuit for each ramp, means for alternately interrupting and restoring the two restraining circuits in passing a live ramp, means for interrupting both circuits in passing a dead ramp, a third controlling circuit for said train stopping means, a circuit closer therefor, an electromagnet acting on the circuit closer to hold it in closed position, a circuit closer in circuit with the coils of the electromagnet and automatic speed limiting means adapted to open the last-named circuit, substantially as set forth.

50 8. A block control system for railway trains comprising train-stopping means, means for restraining operation thereof including an electric circuit, a circuit closer in the circuit, ramps along the track, a shoe 55 on the train adapted to be actuated by the ramps for operating said circuit closer to break the circuit, and means for automatically breaking the circuit on loss of said shoe, substantially as set forth.

60 9. A train control system comprising an air brake controlling valve, a normally energized electromagnet for maintaining the valve in closed position, a gravity-controlled circuit closer for making and breaking the circuit through said electromagnet and a

gravity controlled detent adapted to hold said circuit closer in one position, substantially as set forth.

10. A train control system comprising an air brake controlling valve, a normally energized electromagnet for maintaining the valve in closed position, a gravity-controlled circuit closer for making and breaking the circuit through said electromagnet, a gravity controlled detent adapted to hold said circuit closer in one position, and an electromagnet adapted to hold said detent out of operative engagement with said circuit closer, substantially as set forth.

11. A train control system comprising an air brake controlling valve, a normally energized electromagnet for maintaining the valve in closed position, a gravity-controlled circuit closer for making and breaking the circuit through said electromagnet, a gravity controlled detent adapted to hold said circuit closer in one position, an electromagnet adapted to hold said detent out of operative engagement with said circuit closer, a ramp to move said circuit closer and break the circuit and a second circuit connected to said electromagnet and closed by the action of said ramp said second circuit including a part on said detent, substantially as set forth.

12. A train control system comprising an air brake controlling valve, a normally energized electromagnet for maintaining the valve in closed position, a gravity-controlled circuit closer for making and breaking the circuit through said electromagnet, a gravity controlled detent adapted to hold said circuit closer in one position, an electromagnet adapted to hold said detent out of operative engagement with said circuit closer, a ramp to move said circuit closer and break the circuit, a second circuit connected to said electromagnet and closed by the action of said ramp, said second circuit including a part of said detent, an electromagnet to hold the detent in position against the force of gravity, and a circuit for said electromagnet including said ramp, substantially as set forth.

13. A train control system comprising an air brake controlling valve, a normally energized electromagnet for maintaining the valve in closed position, a gravity-controlled circuit closer for making and breaking the circuit through said electromagnet, a gravity controlled detent adapted to hold said circuit closer in one position, an electromagnet adapted to hold said detent out of operative engagement with said circuit closer, a ramp to move said circuit closer and break said circuit, a second circuit connected to said electromagnet and closed by the action of said ramp, said second circuit including a part on said detent, an electromagnet to hold the detent in position against

the force of gravity, a circuit for said electromagnet including said ramp, and means operated by a train in the block for breaking the latter circuit, substantially as set forth.

14. In a block control system for railway trains, a circuit closer comprising a fixed member and a movable member, a lever engaging the movable member, a cam on the lever, a cam mounted for oscillation beneath the first and adapted to open the circuit at either extreme of its movement and close it in central position, a pump operated by a moving part of the engine, and 15 a piston actuated by the pump to operate the circuit closer, substantially as set forth.

15. In a block control system for railways, a train brake pipe, an operator's brake valve, a pipe leading from said valve 20 to the train pipe, a valve casing in said pipe having an open leak port, a valve to prevent access of air to the leak port, a piston for actuating the last-named valve, a passage leading from a source of fluid pressure to a 25 chamber under said piston, an electrically controlled normally open valve in said passage, whereby pressure is maintained on the piston to hold in closed position the valve actuated thereby, an emergency by-pass pipe 30 leading around said valve and joined at both ends to the operator's brake pipe, a three way cock at the junction farthest from the operator, and a seal for said cock, substantially as set forth.

35 16. A block control system for railway trains comprising train-stopping means, means for restraining operation thereof including an electric circuit, a vertically movable circuit closer therefor, a ramp for each 40 block, a block-signal-controlled circuit for each ramp, a shoe on the train adapted to be actuated by the ramps for lifting said circuit closer to break the main circuit, an auxiliary circuit closed by said circuit closer 45 when lifted, and means for breaking both circuits on loss of said shoe, substantially as set forth.

17. A block control system for railway trains comprising train-stopping means, 50 means for restraining operation thereof including an electric circuit, a vertically movable circuit closer therefor, a ramp for each block, a block-signal-controlled circuit for each ramp, a shoe on the train adapted to be actuated by the ramps for lifting said circuit closer to break the main circuit, an auxiliary circuit closed by said circuit closer when lifted, a switch in the auxiliary circuit, and means on the circuit closer for 55 opening said switch on loss of said shoe, said circuit closer also simultaneously breaking the main circuit, substantially as set forth.

60 18. A block control system for railway trains comprising train-stopping means,

means for restraining operation thereof including a main electric circuit, a circuit closer adapted to open said circuit at either extreme of its movement and close the same in intermediate position, ramps along the 65 track, a roadside battery for each ramp, an electromagnet on the train, a circuit partly on the train and partly on the ground connecting the battery and the electromagnet, an armature for the electromagnet, an auxiliary circuit on the train, a circuit closer therefor moving with said armature, a shoe for actuating the first-named circuit closer to break and restore the main and auxiliary 70 circuits in alternation and means whereby the first-named circuit closer breaks the main circuit on loss of a shoe and also moves said armature to break the auxiliary circuit, substantially as set forth.

19. A block control system for railway 75 trains comprising train-stopping means, means for restraining operation thereof including a main electric circuit, an auxiliary restraining circuit, a circuit closer adapted to open one of said circuits at one extreme 80 of its movement and the other at the other extreme, and a second auxiliary restraining circuit having a gap closed by said circuit closer in the first named extreme position, substantially as set forth.

20. A block control system for railway 85 trains comprising train-stopping means, means for restraining operation thereof including a main electric circuit, a circuit closer adapted to open said circuit at either extreme of its movement and close the same in intermediate position, ramps along the 90 track, a roadside battery for each ramp, an electromagnet on the train, a circuit partly on the train and partly on the ground connecting the battery and the electromagnet, an armature for the electromagnet, an auxiliary circuit on the train, a circuit closer therefor moving with said armature, a shoe for actuating the first-named circuit closer 95 to break and restore the main and auxiliary circuits in alternation, and means whereby the three circuits are broken on loss of a shoe, substantially as set forth.

21. In a train control system, automatic 100 control devices including a main circuit, an auxiliary circuit adapted to be manually closed when the main circuit is broken, an electromagnet having an armature adapted to maintain the auxiliary circuit in closed 105 relation, a circuit closer in the circuit of the electromagnet, and a pump on the train adapted to break the circuit on excessive speed thereof, substantially as set forth.

22. In a train control system, automatic 110 control devices including a main circuit, an auxiliary circuit adapted to be manually closed when the main circuit is broken, an electromagnet having an armature adapted 115 to maintain the auxiliary circuit in closed 120 relation, a circuit closer in the circuit of the electromagnet, and a pump on the train adapted to break the circuit on excessive speed thereof, substantially as set forth.

relation, a circuit closer in the circuit of the electromagnet, a pump on the train adapted to break the last-named circuit on excessive speed thereof; a casing for the pump, a body 5 of liquid in the casing, and means for breaking said last-named circuit when the liquid falls below a predetermined level, substantially as set forth.

23. In a train control system, automatic 10 control devices including a main circuit, an auxiliary circuit adapted to be manually closed when the main circuit is broken, an electromagnet having an armature adapted to maintain the auxiliary circuit in closed 15 relation, a circuit closer in the circuit of the electromagnet, a pump on the train, a hydraulic ram operated thereby, and connections from the piston of the ram to said circuit closer whereby excessive upward movement 20 of the piston breaks said circuit, substantially as set forth.

24. In a train control system, automatic 25 control devices including a main circuit, an auxiliary circuit adapted to be manually closed when the main circuit is broken, an electromagnet having an armature adapted to maintain the auxiliary circuit in closed 30 relation, a circuit closer in the circuit of the electromagnet, a pump on the train, a hydraulic ram operated thereby, connections 35 from the piston of the ram to said circuit closer whereby excessive upward movement of the piston breaks said circuit, and leak ports limiting the upward movement of said piston, substantially as set forth.

25. In a train control system, automatic 40 control devices including a main circuit, an auxiliary circuit adapted to be manually closed when the main circuit is broken, an electromagnet having an armature adapted to maintain the auxiliary circuit in closed 45 relation, a circuit closer in the circuit of the electromagnet, a pump on the train, a hydraulic ram operated thereby, connections 50 from the piston of the ram to said circuit closer whereby excessive upward movement of the piston breaks said circuit, a bypass 55 for the liquid coming from the pump, and means for adjusting the size of the bypass 60 to vary the effect of the pump on the piston, substantially as set forth.

26. In a train control system, automatic 65 control devices including a main circuit, an auxiliary circuit adapted to be manually closed when the main circuit is broken, an electromagnet having an armature adapted to maintain the auxiliary circuit in closed 70 relation, a circuit closer in the circuit of the electromagnet, a pump on the train, a hydraulic ram operated thereby, connections 75 from the piston of the ram to said circuit closer whereby excessive upward movement of the piston breaks said circuit, leak ports limiting the upward movement of the piston, and a leak passage in the piston coop-

erating with said leak ports to enable the piston to sink to the bottom of the cylinder, substantially as set forth.

27. In a train control system, automatic 80 control devices including a main circuit, an auxiliary circuit adapted to be manually closed when the main circuit is broken, an electromagnet having an armature adapted to maintain the auxiliary circuit in closed 85 relation, a circuit closer in the circuit of the electromagnet, a pump on the train, a hydraulic ram operated thereby, connections from the piston of the ram to said circuit closer whereby excessive upward movement of the piston breaks said circuit and an equalizing passage permitting the liquid in the cylinder of the ram to find the same level as that in the casing for the pump, substantially as set forth.

28. In a train control system, automatic 90 control devices including a main circuit, an auxiliary circuit adapted to be manually closed when the main circuit is broken, an electromagnet having an armature adapted to maintain the auxiliary circuit in closed 95 relation, and means for breaking the circuit of the electromagnet on excessive speed of the train, substantially as set forth.

29. A block control system for railway 100 trains comprising train stopping means, a normally closed electric circuit restraining operation thereof, an auxiliary circuit, a ramp for each block, a block-signal-controlled circuit for each ramp, means for alternately interrupting and restoring the two train circuits in passing a live ramp, means for interrupting both circuits in passing a dead ramp, a third controlling circuit for said restraining means, manual means for closing said circuit, a fourth circuit simultaneously closed by said manual means, a circuit closer in the third circuit, an electromagnet in the fourth circuit adapted to hold said circuit closer in closed position, and speed-limiting means for breaking said 110 fourth circuit when the train exceeds a predetermined limit, substantially as set forth.

30. A block control system for railway 115 trains comprising train stopping means, a normally closed electric circuit restraining operation thereof, an auxiliary circuit, a ramp for each block, a block-signal-controlled circuit for each ramp, means for alternately interrupting and restoring the two train circuits in passing a live ramp, means for interrupting both circuits in passing a dead ramp, a third controlling circuit for said restraining means, gravity-actuated manual means for closing said circuit, a fourth circuit simultaneously closed by said 120 manual means, a gravity-actuated circuit closer in the third circuit, an electromagnet in the fourth circuit adapted to hold said circuit closer in closed position, and speed-limiting means for breaking said 125 fourth circuit, substantially as set forth.

circuit when the train exceeds a predetermined limit, substantially as set forth.

31. In a train control system, train stopping means and means for restraining the same from operation comprising a main electric circuit, roadside devices to interrupt the main circuit, an auxiliary circuit supplementing the action of the main circuit when the track is clear, a permissive low-speed circuit, and a circuit closer common to said circuits movable by gravity into position to close the main circuit, said circuit closer being lifted positively by said roadside devices, substantially as set forth.

32. A train control system comprising an air brake controlling valve, a normally energized electromagnet for maintaining the valve in closed position, a gravity-controlled circuit closer for making and breaking the circuit through said electromagnet, a gravity controlled detent adapted to hold said circuit closer in one position, and an elec-

tromagnet adapted to hold said detent out of operative engagement with said circuit closer, substantially as set forth.

33. A train control system comprising an air brake controlling valve, a normally energized electromagnet for maintaining the valve in closed position, a circuit closer biased to close the circuit of the electromagnet, a detent for holding the circuit closer in open position, an electromagnet adapted to restrain the detent from engagement with the circuit closer, roadside devices for actuating said circuit closer to break the circuit, and a second circuit for energizing the first-named electromagnet said second circuit including a part of said detent, substantially as set forth.

In witness whereof, I have hereunto set my hand at Washington, District of Columbia, this 27th day of September, A. D. nineteen hundred and twenty-two.

EARL C. STAFFORD.
